VARIABLE BAND WIDTH RECEIVER

Murray G. Crosby, Riverhead, N. Y., assignor to
 Radio Corporation of America, a corporation
 of Delaware

Application January 8, 1941, Serial No. 373,539

6 Claims. (Cl. 250—20)

This application concerns a variable intermediate-frequency band width frequency modulation receiver wherein the deviation ratio may be changed and the system thereby rendered more adaptable to the reception of weak signals by switching to a lower deviation ratio at the receiver and reducing the deviation at the transmitter. Hence, when the signal is weak, the lower deviation ratio may be used and when the signal is strong enough to allow a higher deviation ratio, it may be used. The improvement in signals bothered by ignition is especially good in this respect. Any of the known variable intermediate-frequency band width methods may be used, for instance, two separate intermediate-frequency filters with a switching system or variable coupling intermediate-frequency transformers.

In one arrangement of automatic deviation ratio adjustment for a frequency modulation receiver, I use a receiver having two intermediate-frequency channels, a broad and narrow one, so that two deviation ratios may be produced. The receiver is set up in such a manner that the narrow intermediate-frequency amplifier is used when the deviation is low in the soft passages of music for instance and the broad intermediate frequency is used in the "forte" passages.

In Figs. 1, 2, and 3, I have shown several modifications of wavelength modulated wave receiving means including circuits of different band pass width with automatic means for deriving the demodulation output from that circuit having a band pass characteristic closest to the width of the band received.

In Fig. 1, a relay is controlled by rectified wave energy to supply output from that receiver whose band pass width is of the order of the width of the band received.

In Fig. 2, rectifiers are arranged and operated to control modulation potential amplifiers in the output of the demodulators of different band widths in such a manner that the output is derived from a circuit having a band pass characteristic of the order of the band pass of the received wave.

Referring to Fig. 1 of the drawings, 4 is a radiant energy pick-up means of any approved type connected with a wave amplifying and, if desired, wave frequency reducing means of the heterodyne type. The output of the receiving amplifier in unit 6 is fed to the input of two wavelength modulated wave amplifiers and demodulators 10 and 12, respectively. One of these amplifiers and demodulators has a band pass such as to accept wave energy with the deviation

ratio $D=N$ where N is any number while the other has a band pass characteristic such as to accept wave energy of a deviation ratio $D=1$.

The output of demodulator 10 is supplied by transformer 20 to a diode detector 40. The winding 25 of a relay 54 is connected in series with the diode detector 40. The armature 56 of the relay 54 connects either the output of 10 or the output of 12, depending upon its position, to the output means or jack 57. Spring 58 holds the armature against contact 41 in the absence of sufficient energizing current from 10.

In operation, when the frequency deviation is low, that is indicating a low amount of modulation on the wave, the output jack 57 is connected to the output of receiver 12 because the pull of the spring 58 overcomes the pull effected by the winding of the relay 54 and the armature is moved to contact 41 by spring 58. When the frequency deviation increases the output of 10 increases so as to cause increased current to flow in tube 40 and energize the winding of relay 54 sufficiently to move the armature 56 to contact 51 to connect the output means 57 to the demodulator of higher band pass characteristic in unit 10.

In this circuit a rectifier 40 is set up to control the choice of two receiver outputs (the one receiver with a deviation ratio $D=1$ and the other with a higher deviation ratio $D=N$). The rectifier 40 is arranged to operate a relay 54 when the level rises above a certain amount. Let us assume a sample case: Audio band=10 kc., $N=10$; then when the frequency deviation is less than 10 kc. the spring overcomes the pull of the relay magnet so that the output jack is connected to unit 12. For higher frequency deviation, the pull of the relay magnet overcomes the pull of spring 58 so that armature 56 is connected to 51 and the jack 57 is connected to receiver 10. Thus, when the signal gets up to a certain level, the pull of the relay magnet overcomes the pull of the spring and pulls the relay tongue 56 to a position to connect the output jack to receiver 10.

In the circuit of Fig. 2, the stronger signal biases down the weaker low-deviation-ratio, signal after a certain signal level has been reached, and at the same time or point, the low-deviation receiver rectified output biases up the audio-frequency amplifier of the high-deviation signal. By proper adjustment of rectified bias, the device may be made to switch the output from the low-deviation receiver to the high-deviation-ratio receiver at

the point where the frequency deviation starts to overload the low-deviation-ratio receiver.

In the modification shown in Fig. 2, two frequency modulated wave amplifiers and demodulators 60 and 70 have their outputs connected by audio frequency amplifiers 61 and 71, respectively, to a combining circuit 73 connected with an output means 75. The outputs of the means 60 and 70 of different deviation ratio are respectively connected by transformers 78 and 82 to diode rectifiers 84 and 86, respectively. Here, the diode rectifiers are biased by adjustable sources 87 and 89. A point between the cathode 83 and resistance 90 of diode 86 is connected to the modulation potential amplifier 61 to control the gain thereof. A point between the anode 85 of the diode 84 and the diode resistor 91 is connected in a similar manner to the modulation-potential-frequency amplifier 71 to control the gain thereof. Both of these gain control circuits may be connected in a well known manner to control electrodes in tubes in said amplifiers to control the gain thereof. Bias battery 92 serves to bias amplifier 61 to cut off, so as to be inoperative in the absence of modulation.

In operation, for low depths of modulation, bias battery 92 makes amplifier 61 inoperative so that output is furnished to 73 from 71. Thus, for the lower depths of modulation, the low-deviation-ratio receiver furnishes the output. When the depth of modulation rises to such a level as would start to overload the low-deviation-ratio receiver, biases 87 and 89 are adjusted to be overcome by the rectified output from transformers 82 and 78, respectively. Hence, at this level, a positive rectified voltage will appear across resistor 90 and a negative voltage across resistor 91. The positive voltage from 90 is fed through bias battery 92 to amplifier 61 so that the negative bias from 92 is overcome by the positive bias from 90 and amplifier 61 becomes operative. At the same time the negative voltage from 91 biases amplifier 71 toward cutoff and tends to make it inoperative. Thus, at this level, the amplifier from the wide receiver is turned off at the same time that the amplifier for the narrow receiver is turned on. This simultaneous biasing of both amplifiers tends to make the changeover action more rapid than it would be if only one amplifier were biased. Somewhere during the change-over cycle there will be a condition of equal output from both receivers so that combining amplifier 73 is necessary to combine the two outputs for this interval.

In the modification of Fig. 3, I have shown an embodiment in which the voltage to be rectified for control is taken via leads 79 from the combined output. The operation is otherwise essentially the same as that of Fig. 2 except that the diode biasing batteries 87 and 89 are eliminated. Elimination of these batteries causes the change-over to be more gradual and continuous instead of abrupt as in the case of Figs. 1 and 2. Such a gradual and continuous change-over is an alternative adjustment which is advantageous in conditions where the difference in signal-to-noise ratio on the two receivers is rather large and the abrupt change would be annoying.

What is claimed is:

1. In a system for receiving frequency modulated carrier waves, at least two parallel modulated carrier wave transmission channels, each channel being adapted to derive the modulation signal from the modulated carrier wave, one of said channels having a relatively wide pass band characteristic thereby to accommodate modulated

carrier waves having a relatively wide frequency deviation range, the second channel having a relatively narrow pass band characteristic, a modulation signal utilization network having connections to each of said channels, a rectifier network connected to rectify the modulation signal output of at least one of said channels, and means responsive to the rectified modulation signal for controlling the effectiveness of the connections between said utilization network and each of said channels.

2. In a system for receiving frequency modulated carrier waves, at least two parallel modulated carrier wave transmission channels, each channel being adapted to derive the modulation signal from the modulated carrier wave, one of said channels having a relatively wide pass band characteristic thereby to accommodate modulated carrier waves having a relatively wide frequency deviation range, the second channel having a relatively narrow pass band characteristic, a modulation signal utilization network having connections to each of said channels, a rectifier network connected to rectify the modulation signal output of at least one of said channels, and means responsive to the rectified modulation signal for controlling the effectiveness of the connections between said utilization network and each of said channels, said connections comprising parallel modulation signal amplifiers.

3. In a system for receiving frequency modulated carrier waves, at least two parallel modulated carrier wave transmission channels, each channel being adapted to derive the modulation signal from the modulated carrier wave, one of said channels having a relatively wide pass band characteristic thereby to accommodate modulated carrier waves having a relatively wide frequency deviation range, the second channel having a relatively narrow pass band characteristic, a modulation signal utilization network having connections to each of said channels, a rectifier network connected to rectify the modulation signal output of at least one of said channels, and means responsive to the rectified modulation signal for controlling the effectiveness of the connections between said utilization network and each of said channels, and said latter control being such that solely the connection between the wide band channel and the utilization network is effective in response to increased modulation signal amplitude.

4. In a system for receiving frequency modulated carrier waves, at least two parallel modulated carrier wave transmission channels, each channel being adapted to derive the modulation signal from the modulated carrier wave, one of said channels having a relatively wide pass band characteristic thereby to accommodate modulated carrier waves having a relatively wide frequency deviation range, the second channel having a relatively narrow pass band characteristic, a modulation signal utilization network having connections to each of said channels, a rectifier network connected to rectify the modulation signal output of at least one of said channels, and means responsive to the rectified modulation signal for controlling the effectiveness of the connections between said utilization network and each of said channels, said rectifier network comprising a diode rectifier coupled to the wide pass band channel output.

5. In combination with a pair of parallel frequency modulated carrier wave transmission

channels, each channel including a demodulator for providing modulation signal output, one of the channels having a pass band to transmit wide frequency deviations of the carrier, the second having a pass band to transmit narrow frequency deviations, independent modulation signal output connections from the channels, a common utilizing network coupled to both output connections, a separate rectifier coupled to a respective one of the output connections to provide rectified modulation signal voltage, and a control connection from each rectifier to a predetermined one of the said output connections to control the effectiveness thereof with said rectified voltage.

6. In combination with a pair of parallel frequency modulated carrier wave transmission channels, each channel including a demodulator

for providing modulation signal output, one of the channels having a pass band to transmit wide frequency deviations of the carrier, the second having a pass band to transmit narrow frequency deviations, independent modulation signal output connections from the channels, a common utilizing network coupled to both output connections, a separate rectifier coupled to a respective one of the output connections to provide rectified modulation signal voltage, and a control connection from each rectifier to a predetermined one of the said output connections to control the effectiveness thereof with said rectified voltage, each of said output connections comprising a modulation signal amplifier, means for biasing each of said rectifiers.
